JACOB REESE, OF PITTSBURG, PENNSYLVANIA.

Letters Patent No. 92,469, dated July 13, 1869.

IMPROVED METHOD OF MAKING BANDS FOR SHINGLE-BUNDLES.

The Schedule referred to in these Letters Patent and making part of the same.

To all whom it may concern:

Be it known that I, JACOB REESE, of the city of Pittsburg, in the county of Allegheny, and State of Pennsylvania, have invented a new and useful Improvement in Manufacture of Fastenings for Bales and Bundles; and I do hereby declare the following to be a full, clear, and exact description thereof, reference being had to the accompanying drawing, making part of this specification, in which—

Figure 1 is a perspective view of my improved cutting-machine;

Figure 2 is a section as formed by a plane passing through the machine at right angles to the cutters;

Figure 3 is a perspective view of one of the shingle-strips made by my machine; and

Figure 4 is a perspective view of a bunch or bundle of shingles, when packed or bound ready for market.

Shingles are now generally put up for market in large bunches or bundles, as shown in fig. 4.

These bunches are secured by wooden bars x x' , placed, one on top, and the other under the bunch, along the line of lap of the shingles. The bunch is compressed, and thin, narrow strips of hoop-iron y y' extend from each end of one bar x to the opposite end of the other bar x' , the ends of the strips being, for greater security, bent over the ends of the bars and nailed, as at y .

These strips y have heretofore been made usually of hoop-iron, by cutting them to the required lengths, and then punching the nail-holes.

Instead of making them from hoop-iron, I cut and punch them by machinery from thin sheet-iron, whereby I am enabled to make them at about one-half the expense now incurred in their manufacture, and, at the same time, produce an article sufficiently strong and durable for the purposes required; and in such mode of manufacture, and in the construction of a machine therefor, consists the nature of my invention.

To enable others skilled in the art to make and use my invention, I will proceed to describe its construction and mode of operation.

By sheet-rolls, of the ordinary or any known construction, I roll out sheet-iron, either in single sheets, or in packs of, say, six sheets, the latter being the most rapid and perfectly practicable, and then cut or shear such sheet-iron crossways, or across the direction of the grain of the iron, into smaller sheets, equal in width to the length of the strips y to be made.

Each of these smaller sheets may be cut across in the opposite direction, so as to divide them still more, for convenience of handling, if so desired, but their width should remain equal to the length of the desired strips y , say twelve or fifteen inches, these being the lengths usually made. Such sheets are then ready to be cut and punched into strips y .

For such cutting and punching, I use a machine shown in figs. 1 and 2, f being a suitable bed or foundation, and g being plumber-blocks, on which the axle h operates.

On this axle is a cam, i , which actuates the arm m' , which extends back from the rocking knife-block m .

This knife-block has a rocking motion on axle-pins or journals o , inserted in its opposite sides, through the uprights f' , and held in place by caps o' .

Near the front of the frame is a T-shaped slot, a .

Over this slot, by T-head bolts c placed therein, and secured by nuts c' , a cutter-block, b , is secured.

To this is bolted a stationary cutter, b' .

The cutter-block b , at the points where the T-head bolts c pass through, is so slotted as to be adjustable, and such adjustment is effected by set-screws d , which pass through the front of the frame f .

To the front of the rocking knife-block m is bolted a knife, n , and the stationary cutter b' is so adjusted, by set-screws d , that the two knives shall operate conjointly, and shear the blanks or strips from the sheet-metal.

Back of the knife n is fastened a gauge, n' , the lower end of which projects below the knife-block m , and is adjusted at a distance from the stationary cutter b' equal to the width of the strips to be made.

This gauge is so slotted as to be adjustable for cutting strips y of different widths, if so desired.

On the front of the knife n are the punches s s' , so made, and so placed and adjusted, that each one will, at every stroke, punch the number of holes required in each end of each strip y .

In the stationary cutter b' , immediately under the points of the punches s , are punching-holes s' , through which the punchings pass down, and out at the mortises s'' below. The stationary cutter b' thus becomes a punching-block.

The cutter b' is so made that the position of one or both the punches s may be changed, to punch the ends of strips of different lengths. Illustrative of this, are the punching-holes and mortise shown at r .

The operation of the machine is, then, as follows:

The small sheet-iron sheets, cut as described, of a width, in the direction of the grain of the iron, equal to the length of the strip y to be made, are fed in between the cutters b n , against the gauge n' . The cam i , on the axle h , as it comes against the arm m' , gives the knife n a downward throw, cutting one strip y off the edge of the sheet, and the punches s punching the nail-holes u in the sheet of the next strip y . The return or upward stroke of the knife n is secured by a spring, z , which is connected by a cord or chain, z' , with a hook, z'' , on the end of the arm m' . Thus, with each stroke of the knife n , I deliver a strip, y , complete. They are then packed in bundles or kegs, or

otherwise put up in packages, and are ready for market and use.

The great and growing demand for them in the shingle-making districts of our country, renders them an important article of manufacture.

The principal advantages connected with such mode of manufacture over the mode of manufacture heretofore adopted, viz, by cutting them from hoop-iron, may be briefly stated as follows:

First, in rolling hoop-iron, the best of charcoal-iron must be used, each bar or strip must be rolled separately, and the iron cannot safely be rolled thinner than to a certain gauge; but by rolling sheet-iron in packs, I roll it out more rapidly, and to a thinner gauge than can be done in rolling hoop-iron, saving time, labor, expense, and material, and, at the same time, am enabled to use a less costly quality of iron, and still secure, in the manufactured strip *y*, all the required strength and durability.

By this mode of manufacture, I am able to effect a saving in the first cost of about one half.

Metallic strips, made substantially as described, are

useful for other purposes, or for securing bundles and bales of other articles, and all such uses of such strips I include in my invention.

I do not claim rolling sheets of metal in packs, nor do I claim cutting strips transversely, as above described, since each by itself is a common mechanical practice; but

What I claim as my invention, and desire to secure by Letters Patent, is—

1. A machine-cut and punched shingle-strip or bale-fastening, made substantially in the manner described, from sheet, as distinguished from hoop-iron.

2. The combination, substantially as described, of the vibratory cutter *n*, gauge *n'*, and adjustable punches *s*, with the stationary cutter *b'*, provided with holes *s'*, for the purposes hereinbefore set forth.

In testimony whereof, I, the said JACOB REESE, have hereunto set my hand.

JACOB REESE.
